SIDNEY CORNELL, OF PAWLING, NEW YORK.

PROCESS AND DEVICE FOR SEPARATION OF OILS.

1,202,969.

Specification of Letters Patent. Patented Oct. 31, 1916.

Application filed January 22, 1916. Serial No. 73,536.

To all whom it may concern:

Be it known that I, SIDNEY CORNELL, a citizen of the United States, and a resident of Pawling, county of Dutchess, State of New York, have invented a certain new and useful Improvement in Processes and Devices for Separation of Oils, of which the following is a specification.

Machine shops, automobile repair houses and garages accumulate from time to time certain quantities of waste oils and greases which are undesirable because of fire hazards, and are of no commercial use, due to the fact that they are mixtures of lubricating oils, burning oils and gasolene.

The object of this invention is the separation of the gasolene, benzin and other oils of a more volatile nature from the heavier lubricating oils, greases, etc., that may exist in the mixture mentioned.

By means of the apparatus herein disclosed the gasolene and benzin are separated clear from the heavier hydrocarbon oils and are refined gasolene or benzin and fit for reuse as such, while the heavier oils remaining in the retort, consisting of a mixture of dirt and lubricating oils, may be further subjected to a treatment of filtration through a filter press to remove the dirt,—after which this oil is available as a fuel oil or for the rougher type of lubricant.

Gasolene and other highly volatile hydrocarbon oils can be vaporized by the introduction of steam of appropriate temperature and pressure, but if a small percentage of animal or vegetable oils is present, as it usually is in the mixtures under consideration, the steam in passing through the body of the liquid emulsifies such animal or vegetable oil, and thereby causes the whole mass to assume an emulsified or frothy condition, in which condition distillation is retarded or completely stopped. In order to enable the more volatile constituents to be separated readily and cheaply from mixtures of the character described, and at the same time to overcome the difficulty which I have indicated, I provide a retort having means for introducing steam into the mixture therein, together with certain heating means in the retort whereby the inimical effect of emulsification is neutralized or the formation of an emulsion or frothy condition actually utilized.

The accompanying drawing illustrates the apparatus mainly in vertical section.

The essentially novel part of the apparatus comprises a retort 10 and the parts therein contained. A mixture of oils to be treated is supplied to the lower part of this retort by suitable means through a pipe 11. A valve 12 in this pipe is indicative of means for controlling the amount of liquid in the retort and maintaining the level at an appropriate height, above the heater 13 and below the heater 14, presently to be described. Steam is introduced into the body of the oil mixture near the bottom of the retort, as by means of a distributing ring 15 provided with a multiplicity of jet openings 70 and connected with a source of steam supply by a valved pipe 16.

The heater 13 consists of a coil of unperforated steam pipe disposed within the liquid-holding lower portion of the retort, 75 and is provided with suitable valve connections 17 and 18 whereby it may be kept full of steam. Another similar heater 14 is located in the vapor dome 31, constituting the upper part of the retort, and has valve 80 connections 19 and 20. A connection 21 may be provided for placing the coils 14 and 13 in series, and the valve 22 therein may be set so as to maintain a difference in pressure and temperature in the two heaters. A pipe 85 23 leads from the top of the vapor dome to a condenser, indicated in a conventional manner at 24, and from the condenser the pipe 25 leads to a separator 26, of known type, from which water of condensation 90 may be drawn off through a pipe 28 and condensed gasolene or the like through a pipe 27. A valved outlet pipe 29 connects the bottom of the retort with a filter press of any suitable or known character, the 95 same being indicated diagrammatically at 30.

In operation the oil mixture is supplied to the retort up to a height covering the coil 13. Saturated steam is then passed through the ring 15. The pressure and corresponding temperature may vary from 10 pounds to 75 pounds. It is preferably 20 pounds. Steam is also admitted to the coils 13 and 14. The pressure of the steam in the coil 13 may be varied from approximately 20 pounds to 50 pounds, though it is preferably higher than that of the steam supplied to the ring 15. The pressure of the steam in the upper coil 14 may likewise be varied between the approximate limits of 20 and 50 pounds, though it will be understood that in general I do not

limit myself to any specific temperatures and pressures. The steam admitted through the ring 15 heats up and agitates the mixture of oils and produces an emulsified condition, 5 which would ordinarily render it impossible to distil the gasoline. The coil 13 preheats the liquid. The injection of the steam through the heated body of oil causes a great deal of frothing, due to the fact that 10 the material is now an emulsion, with the result that the emulsion or froth reaches the upper heater 14. By this contact with the upper heater the separation of the gasoline, benzine, or other like oils, from the emulsion 15 is caused to take place. These volatile hydrocarbons, together with the remaining steam, pass over into the condenser and are there condensed. The residue in the still contains lubricating oil and dirt. At the end of 20 a run, the still being blown out, the residue is forced by means of a pump through the filter press 30, designated, for example, after the pattern of the well-known sugar refining apparatus, in which the dirt is removed from 25 the oil. This oil can then be used as a fuel oil, or if given another treatment of washing with soda, is fit for use as a lubricating oil. It will be understood that the invention is not limited to the precise details of construction shown.

What I claim as new is:

1. Apparatus for separating volatile hydrocarbon oils from oil mixtures, comprising a retort, means for supplying the same with a body of the oil mixture, means acting upon the mixture to produce an emulsified froth comprising a steam inlet below the level of the body, and a heater within the retort above the liquid level constituted to vaporize the 35 volatile constituents of the froth.

2. Apparatus for separating volatile hy-

drocarbon oils from oil mixtures, comprising a retort, means for supplying the same with a body of the oil mixture, means acting upon the mixture to produce an emulsified 45 froth comprising a steam inlet below the level of the body, means separate from the steam inlet for heating the body, and a heater within the retort above the liquid level constituted to vaporize the volatile constituents 50 of the froth.

3. Apparatus for separating volatile hydrocarbon oils from oil mixtures, comprising a retort, means for supplying the same with a body of the oil mixture, means acting upon the mixture to produce an emulsified froth comprising a steam inlet below the level of the body, a heater within the body of liquid above the steam inlet, and a heater within the retort above the liquid level constituted 55 to vaporize the volatile constituents of the froth.

4. The method of separating volatile hydrocarbon oils from oil mixtures, which comprises emulsifying a mixture of oils of mineral and animal or vegetable origin by introducing steam into the same, allowing the resulting frothy emulsion to rise into contact with a heated surface, and conducting off and condensing the vapors thus liberated. 60

5. The method of separating volatile hydrocarbon oils from oil mixtures, which comprises emulsifying a mixture of oils of mineral and animal or vegetable origin by introducing steam into the same, supplying additional heat to the mixture, and causing the frothy emulsion thus produced to contact with a heated surface and thereby liberating the volatile constituents. 75

In witness whereof, I have hereunto set my hand this 24th day of December, 1915.

SIDNEY CORNELL.
